James P. Bedford ^{INVENTOR:}
By Chaffee C. Chapman
ATTORNEY

UNITED STATES PATENT OFFICE.

JAMES P. BEDFORD, OF FOREST HILLS, NEW YORK, ASSIGNOR TO THOMAS R. BROOKS,
OF SCRANTON, PENNSYLVANIA.

DESIGN FOR A SIGNAL ARM.

Application filed November 17, 1928. Serial No. 28,925. Term of patent 14 years.

To all whom it may concern:

Be it known that I, JAMES P. BEDFORD, a citizen of the United States, residing in Forest Hills, county of Queens, and State of New York, have invented a new, original, and ornamental Design for Signal Arms, of which the following is a specification, reference being had to the accompanying drawing, forming part thereof.

Figure 1 is a view in side elevation of my signal arm;

Figure 2 is a view showing the signal arm of Figure 1 in edge elevation;

Figure 3 is a view of the left end of Figure 1; and

Figure 4 is a view of the right end of Figure 1.

My signal arm is a combination of contrasts, that is, the arrow headed end is of white translucent material, while the base end is of silver color and non-transparent, and within the arrow headed end there is the portrayal of an arrow in green, this being indicated in dotted lines so disposed as to illustrate the said color.

I claim:

The ornamental design for a signal arm as shown and described.

JAMES P. BEDFORD.
